INVENTOR

HARRY F. WOERNLEY

BY *Wm. M. Bady*
ATTORNEY

UNITED STATES PATENT OFFICE.

HARRY F. WOERNLEY, OF WILKINSBURG, PENNSYLVANIA, ASSIGNOR TO THE WESTINGHOUSE AIR BRAKE COMPANY, A CORPORATION OF PENNSYLVANIA.

AUTOMATIC CAR, AIR, AND ELECTRIC COUPLER.

Application filed June 1, 1921. Serial No. 474,061.

To all whom it may concern:

Be it known that I, HARRY F. WOERNLEY, a citizen of the United States, residing at Wilkinsburg, in the county of Allegheny and State of Pennsylvania, have invented new and useful Improvements in Automatic Car, Air, and Electric Couplers, of which the following is a specification.

This invention relates to devices for coupling cars and for connecting electric train line circuits between the cars of a train.

In my prior application, Serial No. 243,497, filed July 5, 1918, there is disclosed an electric train line coupler in which a movable contact carrier is actuated by force derived from the coming together of the couplers, which force is, however, stored up during a part of the approach movement, as by the compression of a spring, which spring is then tripped as the final coupled position is reached and by its expansive force serves to project the contact carrier to its extended coupled position.

When an electric coupler of the above type is associated with a car coupler, the resistance set up by the compression of the springs in the act of coupling, tends to prevent the full and complete movement of the car couplers to the coupled position which is particularly necessary with a coupler of the type known as the "tight lock coupler."

One of the principal objects of my present invention is to provide an improved electric train line coupler of the above type, in which the above difficulty is overcome.

For this purpose, I propose to provide an electric coupler in which the force for projecting the contact carrier is stored up during the uncoupling operation, so that during movement to the coupled position, the couplers will not be subjected to resistance tending to prevent the movement to the coupled position.

Other objects and advantages will appear in the following more detailed description of the invention.

In the accompanying drawings; Fig. 1 is a horizontal section of counterpart electric train line couplers in the coupled position, and constructed in accordance with my invention; Fig. 2 a diagrammatic view, partly in section, of car couplers in the coupled position and so much of the electric couplers as is necessary to show the fluid pressure operating connections between the car and

the electric train line couplers; Fig. 3 a horizontal section of an electric coupler, with the parts in the uncoupled position; Fig. 4 an elevational view, partly in section, of the hand operated mechanism for compressing the projecting spring; Fig. 5 a plan view thereof, partly in section, on the line 5—5 of Fig. 4, showing the handle in normal position; Fig. 6 a plan view, showing the handle in position after compressing the spring; and Fig. 7 a section on the line 7—7 of Fig. 5.

As shown in Fig. 1, the electric coupler may comprise a casing 1, preferably adapted to be secured to the car coupler, and containing a movable member or slide 2 carrying a plurality of electric contacts 3, which are adapted to engage corresponding contacts of the counterpart coupler when the couplers are coupled together and the slides carrying said contacts are projected outwardly to the extended position.

Pivottally mounted in the casing on a pin 4, carried by the casing 1, is a lever 5 having one end connected by a pivoted rod 6 to a piston 7 contained in piston cylinder 8 and having pivotally connected to a point near the other end of the lever, a plunger 9 which engages the end of a coil spring 10, so that upon movement of the piston 7 by fluid under pressure, the lever 5 is rocked on the pin 4, to cause the plunger 9 to compress the spring.

Said spring is mounted in a casing 12 having a spherical projection 13 at the front end adapted to engage a corresponding recess in the coupler casing 1.

Adjacent to the pin 4, the lever 5 is provided with an arm 14 carrying a pin 15 and pivotally connected to the contact carrier 2 is a link 16 having a slot 17 at the rear end in which the pin 15 is adapted to engage.

In order to lock the lever 5 and hold the spring 10 under compression, a trigger arm 18 is pivotally connected to one end of the lever and is provided with a hoop 19 adapted to engage a fixed pin 20 when the parts have moved to the position in which the springs are compressed.

For tripping the arm 18 from its locked position, a piston 21 is provided having a stem 22 adapted to engage the arm and subject to the pressure of a spring 23 tending to retract the stem.

Slidably mounted on the arm 18 is a block 110

24 which is normally pressed into yielding engagement with a pin 25, secured to the arm, by means of a finger 26 which engages a leaf spring 27, secured to the arm 18, the block being positioned to engage the end of the stem 22 when the arm 18 is in the locked position.

The fluid pressure operating connections between the car coupler and the electric train line coupler are shown in Fig. 2 of the drawings, a car coupler of the "tight lock" type being shown comprising hook-shaped projections 28, each adapted to engage a corresponding inclined surface of a counterpart coupler and be rigidly clamped together by the spring actuated locking levers 29, which may be released by fluid pressure admitted to pistons 30, in cylinders 31.

The car coupler also serves as a coupler for the fluid pressure pipes, such as the main reservoir pipe 32 and the brake pipe 33. The fluid pressure conduits are arranged in vertical alignment in the actual construction, but in order to clearly show the operation, the brake pipe connection through the coupler is shown in Fig. 2 at one side of the coupler.

The conduit through the coupler for the main reservoir line is controlled by a tappet valve 34, which is unseated at the final part of the coupling movement.

The conduit through the coupler for the brake pipe 33 is controlled by a tappet valve 35 connected to a piston 36. A pipe 37, connected to the tripping piston 21, leads to the brake pipe conduit intermediate the valve 35 and the gasket opening of the conduit, so that fluid under pressure is supplied to said piston, whenever fluid is flowing through the brake pipe conduit.

A brake pipe closing valve 38 is interposed in the brake pipe 33 and is adapted to be operated by a piston 39, the parts being contained in a casing 40.

Fluid under pressure for operating piston 7 may be supplied through a pipe 41 from a source of pressure such as main reservoir 42, the flow of fluid through said pipe being also adapted to operate the piston 39.

A manually operated valve 43 is provided in pipe 41 for controlling the supply and exhaust of fluid pressure to and from the pipe 41 and the pipe 41 contains a check valve 44 for preventing back flow.

The supply of fluid for operating the car coupler piston 30 may be controlled by a relay valve 45 adapted to be operated by a piston 46 for supplying fluid from the main reservoir pipe line 32 through passage 47 to the piston 30 and fluid under pressure for operating the piston 46 is supplied through a pipe 48 and a port 49, controlled by piston 7, and only when said piston has been moved out its full stroke by fluid pressure.

A port 50 leading from the piston cylin-

der 8 to the meeting face of the electric coupler is adapted to register with the corresponding port of a counterpart coupler when in coupled position, so that fluid supplied to one piston cylinder 8 will also be supplied through the ports 50 to the piston cylinder of the counterpart coupler.

In order to retract the contact carrier 2 when relieved of the pressure of the spring 10, a release spring 51 is provided, said spring being interposed between the rear face of the coupler casing 1 and a collar 52 on a tubular rearward projection 53 carried by the slide 2.

In operation, as so far described, assuming that the electric coupler parts are in the uncoupled position, as shown in Fig. 3 of the drawings, with the spring 10 held under compression by the plunger 9 and with the hook 19 of the trigger arm 18 engaging the pin 20. When two cars are brought together for coupling, the counterpart car couplers will engage in the usual manner and in the coupled position, the locking levers 29 will assume the locked position as shown in Fig. 2. In coupling up, the tappet valves 35 are lifted from their seats by the engagement of the tappets, so that communication is established through the brake pipe 33.

Fluid under pressure flowing through the brake pipe conduit of the car coupler then flows through pipe 37 to the tripping piston 21 and said piston thereupon actuates the stem 22, which engages the block 24, so that the arm 18 is shifted, causing the hook 19 to be tripped out of engagement with the pin 20.

Upon release of the arm 18, the lever 5 is turned on its pivot pin 4 by the force of the spring 10 acting through the plunger 9, causing the pin 15 on the arm 14 to act on the toggle link 16, so as to project the contact carrier 2 and thereby effect the engagement of the respective contacts 3 with corresponding contacts of the counterpart coupler.

In order to ensure that the car couplers will be in the full coupled position, before the contact carrier is projected, a volume chamber 11 is interposed between the piston 21 and the pipe 37 and the rate of flow of fluid from said pipe to the chamber 11 is restricted by means of a restricted port 54, so that a predetermined time is necessary for the fluid pressure on piston 21 to increase sufficiently to effect the tripping movement thereof.

In order to uncouple, the cock 43 on one car is turned so as to admit fluid under pressure from the reservoir 42 to pipe 41. The brake pipe closing valve 38 is then operated by piston 39 to close communication through the brake pipe 33 and fluid supplied to the pipe 41 also flows to piston cylinder 8. The piston 7 is then shifted rearwardly and the lever 5 is turned on the pivot pin 4, so that

the plunger 9 is operated to compress the spring 10.

The pressure applied through the pin 15 and link 16 to the contact carrier 2 being now relieved, the release spring 51 operates to retract the carrier 2 to the uncoupled position, as shown in Fig. 3.

When the piston 7 moves out to the end of its stroke, the restricted port 49 is uncovered so that fluid under pressure is supplied through the pipe 48 to piston 46 in the coupler head. The valve 45 is thereupon opened by piston 46 to admit fluid from the main reservoir pipe 32 through passage 47 to the piston chamber 31 and the unlocking piston 30 then operates the locking lever 29 to unlock the car coupler and permit the separation of the cars.

The movement of the lever 5 also projects the arm 18 so that the hook 19 engages the pin 20, the arm being guided by pin 55 so that the pointed end of the hook will pass under the pin 20.

So long as the car couplers are coupled, the piston 21 will be held out by fluid pressure supplied through the brake pipe conduit of the coupler and consequently, as the arm 18 is projected, the block 24 will eventually engage the stem 22. Further movement of the arm 18 to engage the pin 20 is permitted, however, by the fact that the block 24 can move along the arm 18 against the resistance of the spring 21, as the stem 22 presses against the block.

It will also be noted that the spring 27, pressing against the finger 26 exerts a yielding pressure on the block 24 against the pin 25, so that the arm 18 is yieldingly pressed outwardly by the spring to engage the stem 22.

When the cars are separated, the piston 21 is vented to the atmosphere through the opening created at the gasket face of the brake pipe conduit, so that the piston 21 and stem 22 are moved outwardly by the spring 28. As soon as the stem 22 moves out sufficiently, the block 24 will be snapped forward by the spring 27 so as to position in alignment with the stem, as shown in Fig. 3.

Fluid admitted to one piston chamber 8 flows through the registering ports 50 to the piston chamber 8 of the counterpart coupler, so that said coupler is operated in the same manner as the other coupler as will be understood.

The electric coupler parts are now set in position ready for coupling, the spring 10 held under compression by the engagement of the hook 19 with the pin 20 and the coupling operation may now be effected as hereinbefore described.

It will now be seen that the operation of the electric coupler is so interlocked with the operation of the car coupler that in uncoupling, the electric contact carrier will be

retracted before the car coupler can be unlocked and in coupling up, the car coupler will be in its fully coupled position, before the electric contact carrier can be projected to make the electric connections with the contacts of the counterpart coupler.

The movement of the lever 5 and the connected parts is limited by the engagement of a projection 56 with a stop 57 carried by the casing 1.

Since in the coupled position, the pin 15 is almost in alignment with the pin 4 and the pivot pin of the link 16, a high leverage ratio is secured, so that the force of the spring 10 is multiplied to exert a high pressure for firmly maintaining the electric contacts in engagement.

A manually operated mechanism may be provided for operating the lever 5 to compress the spring 10 in case it is desired to permit the retraction of the contact carrier while the cars are coupled and for this purpose a manually operated handle or lever 58 is employed as shown in Figs. 4 to 7.

In addition to effecting the release movement of the contact carrier, the spring 51 also acts in the operation of projecting the carrier to prevent a too violent shooting forward of the carrier by the action of the projecting spring 10, which might cause undue impact and damage of the contact upon meeting, due to the momentum of the carrier.

Said lever has a squared opening at one end adapted to fit a square shank 59 on the pivot pin 4 and the lever 5 is provided with a projecting segment 60 working in a recess 61 provided in the pin 4, the recess being extended to permit a certain amount of relative movement of the pin 4 when operated by the handle 58.

In order to lock the handle in its adjusted position, a cam member 62 is provided, which is pivotally mounted on the casing 1 and is adapted to be manually operated after the handle 58 has been moved to the position shown in Fig. 6, so as to grip and lock the handle. In the normal position, as shown in Fig. 5, the cam 62 is turned to the position shown and the handle 58 is held in normal position by a flat spring 63, secured to the cam member 62.

In operation, if it is desired to compress the spring 10 by manual operation, the handle 58 is moved out of engagement with the spring 63 and by rotating the pin 4, the projection 60 on the lever 5 is engaged by the side wall of the recess 61 so that the lever 5 is turned to compress the spring 10 and thus permit the release spring 51 to retract the contact carrier 2, the handle being locked in this position by the normal operation of the cam member 62, as shown in Fig. 6.

When the handle 58 is in its normal position, the elongated recess 61 permits a rela-

tive movement of the projection 60 and therefore the lever 5, so that the lever can operate as described, without interference from the manual operating means.

5 Having now described my invention, what I claim as new and desire to secure by Letters Patent, is:—

1. In an electric coupler for cars, the combination of a movable member carrying electric contacts, resilient means, a mechanical connection interposed between said means and said member, manually operated means for compressing said resilient means and mechanism for holding said spring under compression.

2. In an electric coupler for cars, the combination of a movable member carrying electric contacts, resilient means for projecting said member, means for compressing said resilient means, and mechanism for holding said resilient means compressed while the coupler is in its uncoupled position.

3. In an electric coupler for cars, the combination of a movable member carrying electric contacts, a mechanical connection to said member, a spring acting on said mechanical connection for projecting said member in the act of coupling, and means for compressing said spring in the act of uncoupling.

4. In an electric coupler for cars, the combination of a movable member carrying electric contacts connected to the respective train line circuits, a spring, means for compressing said spring as a preliminary to uncoupling, and mechanism operated by said spring for projecting said movable member.

5. In an electric coupler for cars, the combination of a movable member carrying electric contacts connected to the respective train line circuits, a spring under compression in the uncoupled position of the coupler, mechanism operated by said spring for projecting said member, a stop device for restraining the spring, and trip means for releasing said stop device upon the coming together of the counterpart couplers.

6. In an electric coupler for cars, the combination of a movable member carrying electric contacts connected to the respective train line circuits, a spring, means for holding said spring under compression in the uncoupled position of the coupler, mechanism operable by said spring for projecting said member, and means for effecting the operation of said mechanism upon the coming together of counterpart couplers.

7. In an electric coupler for cars, the combination of a movable member carrying electric contacts connected to the respective train line circuits, a mechanical connection to said member, a spring acting on said mechanical connection for projecting said member, and means operated by fluid under pressure for compressing said spring.

8. In an electric coupler for cars, the combination of a movable member carrying electric contacts connected to the respective train line circuits, a mechanical connection to said member, a spring acting on said mechanical connection for projecting said member, and means operated by fluid under pressure supplied during the uncoupling operation for compressing said spring.

9. In an electric coupler for cars, the combination of a movable member carrying electric contacts, a spring, operated by said spring means for projecting said member, a device operated by fluid under pressure for compressing said spring, and manually operated means for supplying fluid under pressure to said device.

10. In a coupler, the combination of a coupler head, a movable lock, a fluid pressure operated device for releasing said lock, a movable member carrying electric contacts, a spring for projecting said member, a fluid pressure operated piston for compressing said spring, and a port controlled by said piston for supplying fluid under pressure to effect the operation of said lock releasing device.

11. The combination with a train brake pipe and a fluid pressure operated valve device for controlling communication through said brake pipe, of an electric coupler comprising a movable member carrying electric contacts, a spring, a mechanism interposed between said member and said spring for effecting the projection of said member by the pressure of the spring, and a piston operated by fluid under pressure supplied to said valve device for compressing said spring.

12. The combination with a train brake pipe, a fluid pressure operated valve device for controlling communication through said brake pipe, of a coupler comprising a coupler head, a movable lock, a fluid pressure operated device for releasing said lock, a movable member carrying electric contacts, a spring, a lever mechanism operatively connecting the spring with said member and through which the pressure of the spring is transmitted for projecting said member, a piston operated by fluid under pressure supplied to said valve device for compressing said spring, and a port controlled by said piston for supplying fluid under pressure to effect the operation of said lock releasing device.

13. In a coupler, the combination of a coupler head, a movable lock, a fluid pressure operated device for releasing said lock, a movable member carrying electric contacts, a lever mechanism connected to said member, a spring acting through said mechanism for projecting said member, and a fluid pressure operated device for compressing said spring and for supplying fluid under pressure to said device.

sure for effecting the operation of said lock releasing device.

14. In an electric coupler for cars, the combination of a movable member carrying 5 electric contacts, a mechanical connection to said member, a spring engaging said connection for projecting said member, a fluid pressure operated device for compressing said spring, and a port communicating with 10 said device and adapted to register with a corresponding port of a counterpart coupler for supplying fluid under pressure to the fluid pressure operated device of the counterpart coupler.
15. In an electric coupler for cars, the combination of a movable member carrying 15 electric contacts, a spring, a lever mechanism interposed between said member and

said spring for projecting said member by the pressure of the spring, means for compressing said spring in the uncoupling operation, and a spring for retracting said member.

16. In an electric coupler for cars, the combination of a movable member carrying 20 electric contacts, a spring, a lever mechanism interposed between said member and said spring for projecting said member by the pressure of the spring, fluid pressure means for compressing said spring in the 25 uncoupling operation, and mechanically operated means for also compressing said spring.

In testimony whereof I have hereunto set my hand.

HARRY F. WOERNLEY.
